COLLAR POINT STIFFENER

Joseph De Benedetti, Oakland, Calif.

Application November 2, 1932, Serial No. 640,744

9 Claims. (Cl. 2—132)

The invention relates to a device for application to the point portions of a turndown collar of a garment for maintaining said collar point portions in smooth and unwrinkled condition.

5 An object of the invention is to provide a device of the class described which is readily adjustable for operative application to collars of different designs wherein the collar point portions extend different distances from the fold edges of the collars.

10 Another object of the invention is to provide a collar point stiffener which is operative to resiliently maintain the stretched and stiffened collar point portions in generally fixed relation to the opposed shirt portion and with the tips thereof adjacent the shirt.

15 A further object is to provide the foregoing features entirely through the provision and use of a stiffening unit which is applicable to turndown collars of standard construction.

20 The invention possesses other objects and features of advantage, some of which, with the foregoing, will be set forth or be apparent in the following description of a preferred embodiment 25 of the device and in the accompanying drawing, in which,

25 Figure 1 is a front elevation of a stiffener unit embodying the present invention.

Figure 2 is an edge view of the unit.

30 Figure 3 is a view showing the stiffener unit in operative association with a turndown shirt collar and a necktie, the unit being shown in dotted lines by reason of its concealment behind the outer collar portion and the tie.

35 Figures 4 and 5 are enlarged sections taken at the lines 4—4 and 5—5 respectively in Figure 3.

40 Figure 6 is an enlarged view showing the lower portions of a strut member of the device, a portion of the structure being broken out for disclosing the operative relations of certain elements of the assembly.

45 Figure 7 is a developed view of the elements shown in Figure 6.

Figure 8 is an enlarged section taken at 8—8 in Figure 6.

50 Figure 9 is an enlarged perspective view of an element of the strut member.

As particularly shown, the features of the present invention are embodied in the structure of a unit 11 which essentially comprises a pair of similar members 12 connected adjacent their tips by means of a crossbar 13. For a reason to be hereinafter brought out, the members 12 are of adjustable length, said members comprising upper and lower sections 14 and 15 which are mutually engaged for relative adjustment longitudinally thereof. Preferably, and as shown, the upper sections 14 and the crossbar 13 are integrally related and are shaped of a single piece 55 of resilient wire of required size and resiliency

for accomplishing certain purposes to be hereafter brought out.

By way of illustration, the present stiffener unit is shown in Figures 3, 4 and 5 as operatively associated with a turndown collar 16 having inner and outer parts 17 and 18, a shirt 19 mounting the collar, and a necktie 21 having neckband portions 22 thereof engaged in the fold 23 of the collar and a knot portion 24 thereof disposed between the collar point portions 25. The knot portion 24 of the necktie 21 is arranged to more or less conceal the overlap of the ends of the inner collar part 17 in a usual manner, and a button 26 is operative at said overlap. The collar 16 may be either releasably or permanently attached to the garment 19, the specific relation being generally immaterial to the present invention. It is noted that the collar points 25 lie opposite the garment front 27 and comprise those portions of the outer, or facing, part 18 of the collar which extend from the ends of the collar and between the collar tips 28 and the collar edge 29 which is defined by the collar fold 23 externally thereof.

It will now be noted that the members 12 of 25 the unit 11 are arranged for concealed installation behind the collar points 25 and extend within the fold 23 for engagement with and between the collar tips 28 and the collar material at the top of the fold 23 whereby they may be operative as 30 struts to stretch and stiffen the collar point portions, particularly when such portions are soft or limber as in a soft or unstarched collar. The members 12 are of similar structure but have their elements in mutually complementary, or right-and-left-hand arrangement for use at the right and left side points of a collar; accordingly, the following description of the elements thereof will be understood as applying to either and both of the members 12. Since the point portions of 35 40 collars of different manufacture or design may have different widths as measured from the collar tips to the top collar edge, the present construction of each member with the mutually adjustable sections 14 and 15 will be understood as providing for a maximum operative length of the member when the same is operatively associated with a collar point.

Referring now to the disclosed structures and relation of the sections 14 and 15 of the members 50 55 12, the section 15 is seen to comprise an element which is generally tubular for receiving the lower end of the section 14 in adjusted relation therein. At its upper end, the section 14 is provided with a rounded bend or crook portion 31 for use as a thrust bearing within a collar fold. A V bend is provided at the lower end of the strut section 14, and the bent back portion 32 thereat is formed with a lateral offset 33 therein providing a detent, said detent lying in the plane of the V bend 60

and extending outwardly of the space defined in the bend. Since the section 14 is shaped of resilient material, the portion 32 is understood to provide a resiliently displaceable mounting for the detent whereby said portion and the detent may be displaced in the plane of the V bend while its restoration to its normal position is resiliently urged; in this manner the structure provides, in effect, a spring detent.

10 The tubular element 15 is of generally elliptical cross-section whereby its bore provides a space of elongated cross-section thereacross and for receiving the V bend of the member 14 in the plane thereof. Notches 34 are provided along and 15 through one edge of the element 15 for selectively receiving the detent 33, said detent arranged to be constantly displaced away from the section 14 while disposed in the bore of the element 15; in this manner, the detent is constantly urged 20 outwardly to engage or remain in a notch 34. For releasing the strut sections for mutual adjustment, the detent 33 may be pressed inwardly by use of a fingernail applied thereto through the notch 34 thereat, it thus being understood 25 that the sections 14 and 15 are arranged to be positively and releasably held in any one of a plurality of adjusted relations.

30 A prong 36 is provided at the lower end of the element 15 for removable engagement in a collar tip. As is particularly brought out in Figures 6 to 9 inclusive, the prong 36 comprises part of an element 35, said element shaped of a single piece of relatively stiff wire or the like. In its present embodiment, the element 35 comprises the prong 36, a guard portion 37 extending perpendicularly from the base of the prong, a portion 38 extending perpendicularly from the portion 37 and in perpendicular relation to the common plane of the prong and the portion 37, a portion 39 making a 35 right angle with the portion 38 and in parallel opposition to the prong, a U-shaped portion 41 having its plane perpendicular to the portion 39, and an end portion 42 perpendicular to the plane of the portion 41 and in parallel opposition to the prong 36. It is noted that the various portions 40 of the element 35 are integrally associated in end-to-end relation, and that the portion 41 and prong 36 lie at opposite sides of the plane defined by the portions 38, 39 and 42.

50 As is particularly brought out in Figures 6 to 8 inclusive, the element 35 is so mounted at the lower end of the element 15 that the guard portion 37 of the element 35 extends through a flat front wall portion 43 of the element 15, the mutually coplanar portions 38 and 39 and 42 lie within the bore of the element 15, and the portion 41 lies transversely against the lower end of the element 15 to extend beyond the other flat wall portion 44 of the latter element. The portion 41, it is noted, provides a guard for the lower end of the element 15 whereby the more-or-less sharp lower end of the wall portion 44 thereat may be held out of engagement with the garment front 55 27, this functioning of the portion 41 being illustrated in Figure 4. In addition to the extension of the guard portion 37 through a perforation of the wall 43 and the bearing of the portion 41 against the lower end of the element 15, the sides 60 43 and 44 of the element may be pressed against and partially around the portions 39 and 42 for completing a firm securing of the element in its mounted position.

65 By reference to Figure 7, it will be noted that 70 the element 15 is adapted for shaping from a

75 rectangular blank 15' having perforations 34' therein to provide the notches 34 when the element is shaped from the blank. With the element 35 placed thereon in its appointed position, the side edges of the blank 15 may be brought 80 into mutual abutment at the front wall portion 43 and in a line through the perforation which receives the guard portion 37 of the element 35, said perforation provided by complementary notches in said edges. In this manner, the pre- 85 formed element 35 may be mounted on the element 15 in fixed unitary association therewith. It will now be clear that, with the strut member 12 adjusted to an appropriate length thereof, the insertion of the prong 36 in the collar tip 15 28 to the limit imposed by the prong guard 37 provides a lower bearing for the strut member whereby it may be compressedly engaged between the collar tips and the fold 23 for smoothing and/or stiffening the collar point in the indicated 20 manner.

90 It will now be noted that the two strut members 12 of the unit 11 are generally coplanar both before and after an operative mounting of the unit on a collar. The crossbar 13 extends 95 from and between the ends of the bends 31 at points of the members 12 inwardly of the line of the extreme upper ends of the members, the spacing of said points from said line being no less than the width of the tie portions 22 adjacent the tie knot. The crossbar 13 comprises generally aligned end portions 45 and a connecting arcuate portion 46. Preferably, and as particularly shown in Figure 2, the unit portions 31 and 45 lie generally in a cylindrical surface 35 of curvature approximating that of the collar, while the portion 46 extends obliquely downwardly and outwardly from such surface of curvature and the plane of the members 12.

100 In mounting the unit 11 in operative association with the collar 16 and necktie 21, the loop ends 31 of the strut members are preferably engaged between the outer sides of the tie portions 22 in the fold 23 and the collar portions 25, and the crossbar 13 is placed behind the tie knot 24, it being noted that the tie portions 22 cross over the crossbar at and above the end portions 45 thereof. It will be understood that the aforesaid disposal of the tie portions 22 above the crossbar portions 45 retains the tie knot in its appointed place between the collar points. When the collar tips 28 engage the garment front 27, the central crossbar portion 46 is preferably arranged to be deflected from its normal relation in the unit 11 by reason of its engagement with the back of the knot 24; in this manner, the collar tips are resiliently held against the garment front, it being noted that the unit is generally operative as a bell-crank lever having its fulcrum at the points where the strut ends 31 105 engage the necktie band portions 22. The unit 11 is thus understood to be inherently operative to both smooth and stiffen the collar points and to hold the points inwardly against the garment.

110 Normally, and as shown in Figure 1, the strut members 12 are convergent from their upper ends, said members assuming the approximately parallel relation shown in Figure 3 when the unit is operatively installed in association with a collar and necktie. By reason of the integral structure 115 of the assembly comprising the unit portions 13 and 14, and the formation of such assembly with resilient wire, the unit 11, while accomplishing the purposes set forth, does not, because of its resiliently yielding qualities, interfere in any 120 75

way with the comfort of a person wearing the garment.

From the foregoing description taken in connection with the accompanying drawing, the advantages of the construction and method of operation will be readily understood by those skilled in the art to which the invention appertains, and while I have described the principle of operation, together with a device which I now consider to be a preferred embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. In a collar point stretcher for use with different turndown collars having point portions of differing lengths as measured from the fold of the collar, elongated strut members for operative disposal behind collar point portions, a cross-bar element connecting said members in unitary association, and adjustable means to adjust the length of each of said members to conform to the length of the collar point portion to be stretched therewith, and a releasable means for positively maintaining the adjusted length of each of said strut members whereby the member is arranged to operatively extend between the tip of said collar point and said collar fold.

2. In a collar point stretcher for use with a turndown collar having complementary collar point portions extending from the fold of the collar, elongated strut members for concealed and operative disposal behind said collar point portions, a cross-bar connecting said members in unitary association, means on each member for fixedly engaging the tip of said collar, and adjustable means to adjust the length of each of said members whereby the disposal of the other end of the member in said fold while the first end engages the collar tip may be arranged to longitudinally compress the member as a strut between said fold and collar tip and thereby stretch the said collar point portion and releasable means normally operative for positively maintaining the adjusted length of each of said strut members.

3. In a stretcher for the point portions of a turndown collar, a pair of strut members extending from a common cross-bar element and each comprising an upper section formed of wire and shaped with a return bend at its upper end providing a thrust bearing for insertion in the fold of the collar, a lower section telescopically receiving the lower end of the first section, adjustable means coactive between the sections to positively and releasably secure them against relative movement and in any one of a plurality of adjusted relations whereby to provide for the adjustment of the effective length of the member, and a prong carried by said lower section for a limited and fixed degree of engagement in the tip of the collar point.

4. In a stretcher for the point portions of a turndown collar, a pair of strut members extending from a common cross-bar element and each comprising an upper section formed of resilient wire having a lower part turned back to define a V point at the lower end of the section an offset in said turned-back part extending out-

wardly from the V in the plane thereof, a lower tubular section of the member telescopically receiving said lower end of the first section therein, notches in said lower section for selectively receiving said offset whereby the same is operative 5 therein as a detent to releasably retain said sections against relative longitudinal movement thereof, and a prong carried by said lower section for a limited and fixed degree of engagement in the tip of the collar point from the back thereof. 10

5. In a stretcher for the point portions of a turndown collar of a garment; a pair of strut members extending from a common cross-bar element and each comprising telescopically engaged upper and lower sections; adjustable means 15 cooperative between said strut sections of each member to positively secure the sections in adjusted relation; means on each upper strut section providing a thrust bearing at the upper end thereof; and a terminal element at the lower end 20 of each lower section fixed thereto and providing a prong for piercing the collar tip, a guard portion to limit the degree of engagement of the prong in the collar tip, and a second guard portion engageable with the garment for preventing 25 the direct engagement of the lower end of the lower said section with the garment.

6. In a stretcher for the point portions of a turndown collar, a cross-bar, strut members extending from the extremities of the cross-bar for 30 engagement as struts between the tips of the collar point portions and the collar fold and each comprising a pair of telescopically engaged elements, and detent means coactive between the elements of each strut member to releasably secure the same in longitudinally adjusted relation 35 whereby the strut member may be fitted to a collar point for operative engagement therewith.

7. In a stretcher for the point portions of a turndown collar, a crossbar, elongated strut members of adjustable length extending from said crossbar for operative disposal behind different collar point portions for stretching the latter, and releasable means normally operative for positively maintaining the length adjustment of each 45 of said strut members.

8. In a stretcher for the point portions of a turndown collar, a pair of strut members extending from a common crossbar element and each comprising an upper section formed of wire and 50 shaped with a return bend at its upper end providing a thrust bearing for insertion in the fold of the collar, a lower section telescopically receiving the lower end of the first section, and adjustable means coactive between the sections to positively and releasably interlock the sections against relative movement and in any one of a plurality of adjusted relations whereby to provide for the adjustment of the effective length 55 of the member.

9. In a stretcher for the point portions of a turndown collar, a crossbar, strut members of adjustable length extending from the extremities of the crossbar for engagement as struts between the tips of the collar point portions and the collar 60 fold and each comprising a pair of mutually aligned and engaged elements, and interlocking means coactive between the elements of each strut to releasably secure the same in longitudinally adjusted condition.

70

JOSEPH DE BENEDETTI.
